UNITED STATES PATENT OFFICE.

EDWARD A. LONG, OF NEW CASTLE, PENNSYLVANIA.

DESIGN FOR A BUILDING BLOCK.

Application filed June 6, 1925. Serial No. 13,692. Term of patent 14 years.

To all whom it may concern:

Be it known that I, EDWARD A. LONG, a citizen of the United States, residing in New Castle, in the county of Lawrence, State of Pennsylvania, have invented a new, original, and ornamental Design for Building Block, of which the following is a specification, reference being had to the accompanying drawings, forming a part thereof.

In the drawings Figure 1 is a front or face elevation of a building block showing my new design. Figure 2 is an end elevation of the same.

I claim:

The ornamental design for a building block, substantially as shown.

EDWARD A. LONG.
